UNITED STATES PATENT OFFICE.

CARL O. EKVALL, OF BROOKLYN, NEW YORK, ASSIGNOR TO GENERAL PAPER GOODS
MANUFACTURING CO., OF NEW YORK, N. Y., A CORPORATION OF NEW YORK.

PATCH-APPLYING MECHANISM FOR WINDOW-ENVELOPS.

1,250,995.

Specification of Letters Patent. Patented Dec. 25, 1917.

Application filed November 30, 1915. Serial No. 64,220.

To all whom it may concern:

Be it known that I, CARL O. EKVALL, a citizen of the United States, residing at 8678 Bay Park Way, in the city of New York, borough of Brooklyn, county of Kings, and State of New York, have invented certain new and useful Improvements in Patch-Applying Mechanism for Window-Envelops, of which the following

10 is a specification.

This invention relates to a machine for manufacturing the well known type of envelop known as the "outlook" or "window" envelop, wherein an opening is formed in 15 the body of the envelop blank and a strip of thin transparent paper or like material is secured over the opening so that the address which is placed on the inclosure in such manner as to register with the opening, can 20 readily be seen through the transfer strip placed over the opening.

This machine relates to the steps in the manufacture of this type of envelop wherein the envelop blank, which has been already 25 ready formed by other machines or processes, is gummed, folded and the patch of transparent material applied over the address opening. The object of this invention is to simplify the mechanism of a machine of this type, to produce a machine which will work with greater speed than heretofore, whereby the output will be increased and to eliminate the general step by step features of the present machines of 30 this character.

These and other objects are accomplished by my invention, a more particular description of which will appear below.

Reference is to be had to the accompanying drawings forming part of this application, in which—

Figure 1 is a side elevation of the portion of my improved machine for gumming the envelop blanks, portions of the same being shown in section;

Fig. 2 is a plan view of the machine, portions of the same being shown in section;

Fig. 3 is a view of the portions of the machine used for removing the patches from the pile and transporting the same to the

plunger which folds the envelop blanks and applies the patches;

Fig. 4 is an elevation of the mechanism for moving the patch grippers to the plunger;

Fig. 5 is a view of the patch holding means and transporting mechanism for the patches;

Fig. 6 is a sectional view on the line 6—6 of Fig. 5, looking in the direction of the arrow;

Fig. 7 is a side elevation of the grippers;

Fig. 8 is a plan view of the same;

Fig. 9 is a plan view of an envelop blank;

Fig. 10 is a plan view of the plunger for creasing the envelop blanks and applying the transparent patches thereto;

Fig. 11 is a sectional view of the air pump for the plunger; and

Figs. 12, 13, 14 and 15 are diagrammatic views showing the method of operation of the plunger.

Throughout the various views of the drawings, similar reference characters designate similar parts.

In the embodiment of my invention, as I have shown it herein, I have not embodied many features of construction peculiar to machines for making envelops, as they are well understood and need no specific description here for the purpose of making my invention clear.

A pile of blanks, as at 1, Fig. 1, is placed upon the table or suitable support 2. Above this is a frame 3. In this frame are bearings 4 in which a rod 5 is carried. This rod 5 is given an up and down movement by a series of levers, the inner lever 6 being fulcrumed to the upright 7 of the frame, and its other end is pivotally connected to a link 8 which is secured to the rod 5 by the clamp 9. Mechanism is secured to the levers operated by a cam or other desired means (not shown) in the machine, for moving the levers so as to give the rod an up and down movement.

The rod 5 carries a head 10. To this head are pendently secured three gumming dies or pickers 11, 12 and 13. These dies are each conformed to the shape of the line of gum which is to be applied to the blank and

their lower edges provided with rubber strips 14 so as to give an even impression of the gum. The dies 11 and 13 are employed for the purpose of applying the gum to the 5 upper and lower flaps of the envelop blanks, and the die 12 is so shaped that it will apply the gum around the opening previously formed in the blank, such as shown at 15 in Fig. 9.

10 The gumming rolls 16 are mounted on a shaft 17 located underneath the gumming dies 11, 12 and 13, the shaft 17 being supported to rotate in blocks 18, which blocks are secured to rods 19, Fig. 2. Arms 20 are 15 secured to the blocks on the rods and connected with some portion of the envelop making machine which will give them a reciprocating movement in the usual way, as indicated by the arrows in Fig. 2.

20 Located below the gumming dies 11, 12 and 13 and the gumming rollers is a stripper plate 21, shown in plan in Fig. 2. This plate is provided with apertures 22 suitably formed and conforming to the shape of the 25 gumming dies, the under surface of which is provided, adjacent to the edges of the apertures 22 with the stripper flanges 23, so as to aid in the stripping or removal of the gummed blanks from the gumming dies.

25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810

11, 12 and 13. These dies 11, 12 and 13, on their downward movement, pass through the apertures 22 in the stripper plate 21, place gum on the edges of the flaps 24 and 25 of the envelop blank, and adjacent the edges of the opening in the blank, as shown at 15 in Fig. 9. The blank adheres to these dies 11, 12 and 13 and is carried upward on the return movement of said dies, and during such upward movement the blank is brought into contact with the stripper plate 21 which arrests its upward movement and frees it from the gumming dies. The flanges 23 act as knife edges to more effectively effect this separation. As the blank is stripped from the stripper plate, it drops down onto a carrier. This carrier consists of two arms 26 having at their ends gripping hooks 27. These arms are adapted to slide or reciprocate in guide ways 28 formed in arms 29 formed on the plate 30, which latter constitutes the upper horizontal portion of the frame, which is called the creasing frame. The arms 26 at the rear are connected together by a rod 31, which in turn carries a link 32, and the link 32 is connected by a lever 33 to a part of the envelop machine which will give it an oscillating movement, producing through the before mentioned connections a reciprocating movement of the carrier.

The horizontal plate 30 of the creasing frame is provided with an aperture 34. This aperture is bounded by front and rear cross plates 35 and by two side plates 36.

These plates constitute an essential element 65 of the folding mechanism to be described. They also form the immediate support for the envelop blank, at the time the patch hereinafter to be described is applied thereto.

In order to decrease the time hitherto used in moving the gummed blank from the gumming dies to the folding box, so-called, thereby increasing the output of the machine, and further in order to avoid the use 75 of mechanism involving a dwell or halt, had for the purpose of applying the patch to the blank intermediately of the gumming and folding operations, or in other words, to eliminate the step by step feature of the 80 structures which have been employed in patch applying appliances prior to my invention, and to produce a patch applying appliance which is continuous in its operation, I have evolved means for selecting a 85 single patch from a superimposed pile of patches, carrying them each singly to a plunger which in turn carries them to the blank, which has already been gummed around the opening, so that the creasing plate, as above 90 stated, forms an essential element of the folding mechanism, and acts as a support for the blank at the instant of the application of the patch to the blank. The close proximity of the patch applying mechanism 95 to the gumming mechanism prevents the gum from drying or flowing, so that a very much more evenly and perfectly applied patch results than has heretofore been accomplished in machines in which mechanism 100 has been interposed between the gumming and folding device for applying the patch, the use of which produces a halt or step by step operation in the machine.

The plunger also constitutes an essential 105 and necessary element of the mechanism for folding the flaps of the blank, and therefore, all mechanism interposed between the folding mechanism and the gum applying mechanism is eliminated and the patch applied simultaneously with the folding of the blank.

In carrying out this part of my invention, I provide the frame 3 with guides 37, which guides carry a tubular rod 38. This rod is 115 given an up and down or reciprocating movement properly timed with respect to the reciprocating movements of the rod 5, Fig. 1, and carrier frame, to the end that the movement of the envelop blank from the completion of the gumming operation to the inception of the folding operation will be continuous, and the application of the patch to the blank will be had without any interruption of that movement. The tubular rod carries a projection 39 to which is pivoted a link 40, to which is pivoted a lever 41 leading to an appropriate part of the ma-

chine, which, through its operation, will raise and lower the tubular rod 38 in synchronism with the other movements heretofore described.

5 The plunger 43, which forms part of the blank folding and patch applying mechanism is shown in section in Figs. 12, 13, 14 and 15 which show the various steps in the folding and patch applying operation. A 10 plan view of the plunger is shown in Fig. 10. The plunger is secured to the lower end of the tubular rod 38 and consists of a suction plate having a recess 44 and a series of holes 45, leading from the recess to 15 a series of channels or ducts 46, which connect said holes and which extend to the opening 47 which ends through the rod 38. For producing the necessary suction, a 20 pump such as shown in Fig. 11 may be used and suitably connected to the rod 38 so that air will pass through said rod to the plunger, the operation of the pump in no manner interfering with the reciprocating movement of the rod 38.

25 In Fig. 3 is shown in detached form the mechanism for lifting a patch from a pile and in Figs. 4, 5, 6, 7 and 8 is shown the mechanism for conveying the patch to the plunger, said latter mechanism involving 30 means for drawing the patch over the surface of the suction plate synchronously with the suction movement of the pump, which effects the flattening or ironing out of the patch so that it will be applied to the envelope blank in a perfectly flat and unwrinkled condition. Such mechanism also includes devices for holding the patch in contact with the plunger for a greater portion of the downward movement of the same 35 after it has passed the creasing plates, the release of the plunger from the applied patch being had at a predetermined point before the commencement of the operation of final laying down of the envelop flaps.

40 The mechanism by which these various operations and results are secured is substantially as follows:

At 48 is a table or support located at one side of the creasing frame and some distance 45 below the level of the creasing frame. This mechanism is primarily supported on two brackets 49 and 50, which form part of flanges or securing plates 51, 52. These securing plates are provided with slots 53 through which bolts 54 pass securing the brackets to the bed plate 48. This method of securing the brackets to the bed plates enables the mechanism supported thereby to be removed or attached as a whole and additionally allows of an adjustment of that mechanism in its entirety laterally of the line of movement of the gummed blank, for a purpose hereinafter to be described. The patches 55, which are of very thin, trans-

parent paper, and are well known, are placed 65 upon a supporting plate 56 which in turn is primarily supported by a racked bar 57, which with other mechanism provides means for bodily adjusting the pile of patches 55 upwardly from time to time, as may be necessary. The plate 56, with its supported layer of patches, is held within a cage 58 having flexible side arms 59 which cage is secured to the bed plate 52 by a flange 60, as shown in Fig. 6. For raising or lowering the plate 56 and its superposed patches 55, I provide the following mechanism:

A recess 62 is formed in the under portion of the bed plate 48 and an aperture 63 extends through the plate 52 above the recess. The racked bar 57 passes through this aperture 63 and into the guiding portion of the guide bar 64, which is secured beneath the bed plate 52, below the recess 63 and extends through the aperture 62, the 80 guide bar having bearings 65 carrying the shaft 66. This shaft 66 is mounted to rotate in a bracket 67 secured to the edge of the bed plate 48, and is provided with a pinion 66^a which engages the racked bar 57 90 and through which the bar is raised or lowered. The shaft 66 is also provided with a turning knob 68 at its end. At 69 is a ratchet wheel and at 70 a spring pressed dog which engages with the teeth in the ratchet wheel. This arrangement permits, by the turning of the shaft 66, the step by step or graduated raising of the table 56 which supports the layer of patches. To lower the patch carrying plate 56, the dog 70 is freed from the ratchet 69, which allows of the plate being lowered to the desired point. As shown in Fig. 6, the opening in the bed plate 48 is of sufficient dimension to allow bodily adjustment.

The pinion 66^a is connected to the shaft by a feather and spline or any like well known means so that the shaft 66 can move bodily through the bearings in the guide 64 and bracket 67 and the racked bar and parts directly associated with it may be moved bodily in the direction of the length of the shaft 66, if desired, when the plates 51 and 52 are adjusted.

Mechanism for lifting a patch from the pile.

The cage 58 is provided with an upright 71, in which is pivoted a collar 72 which carries a tubular rod 73 provided at its forward end with a downwardly bent and laterally extending nipple 74 provided with a plurality, preferably two, holes 75 leading to the interior of the tube. As shown in Fig. 2, this nipple extends crosswise and substantially over the patch 55, and is located adjacent one end of the same and near the gripper to be described.

The rear end of the tube is supported on

a grooved block or pulley 76 which block is slidably mounted upon a shaft 77. This shaft is secured to and extends from one end of a rocker arm 78, the rocker arm being pivoted to a bracket 79 which in turn is secured through its flange 80 to the bed plate 48. The other arm of the rocker 78 is connected by a connecting rod 81 to the driving mechanism of the machine in such a way that when the rod is pulled downwardly, the tubular rod 73 will be tilted downward toward and to the topmost of the pile of patches, at which time the gripper mechanism to be described is out of the way or at its rearmost point of removal from the operative relationship with the pile of patches. The air in the tubular rod 73 is exhausted either by connecting with the exhausting pump which operates in connection with the plunger of the folding operation or may be connected with an exhausting pump operating independently of the aforesaid pump, the exhaustion of air and the release of the suction being synchronized with the operation of the gripping mechanism, as herein-after described.

A spring 82 is secured at one end to the upright 71 and at the other end to the rod 73. The return or lifting movement of the connecting rod 81 lowers the grooved block, allowing the spring to tilt the rod 73. Before this is accomplished, the nipple 74 on the rod 73 has caused one end of one of the patches to become attached thereto, and the action of the spring 82 in tilting the nipple end of the rod, leaves one end of the patch up, as shown in Figs. 3 and 5, to a height which will cause its forward edge to lie in line with guiding plates, to be described; simultaneously, the gripper to be described comes into operation, grips the end of the blank and moves it bodily into the guiding plate. Immediately upon the patch being co-operatively engaged with the guiding plates, and the gripper, the sleeve 83, which is movably mounted on the rod 84, is given a movement in the direction of the plunger and the folding mechanism which carries the gripping device and the patch directly to and under the suction plate of the plunger, where the operation of drawing the patch across the face of the suction plate under the pressure of the suction, as before described, occurs.

The sleeve 83 carries a link 85 which is in turn connected to a lever 86 in its turn being connected with some apertured moving part of the envelop machine which will give it an oscillatory movement properly timed in connection with the gripping action of the gripper mechanism and the sucking action of the folding plunger.

The sleeve 83 is provided with an arm or projection 87 projecting laterally of the sleeve and out toward the cage 58. The pro-

jecting arm has flanges 88. These flanges carry a rod 89 upon which is mounted a spiral spring 90, one end of the spring being secured to one of the flanges and the other to the rod, the spring closing the upper or pivoted arm 91 of the gripper, which arm is fixed on the rod 89. The lower or fixed arm 92 of the gripper is secured by means of the bent portion 93 to the arm 87 so as to lie below the arm 91 of the gripper. 75

For a purpose hereinafter to be described, the lower arm 92 of the gripper is provided with a transversely extending aperture through which extends a button 94, preferably made of leather, having an enlarged 80 head to keep it in place under the arm, it being held in place by a flat spring 95 secured to the under side of the arm 92 by the screw 96. The oscillatory shaft 89 is provided at the end opposite the gripper arms 85 with a tripper arm 97, which carries a roller 98 at its extremity.

The tripper arm 97 has a lug 99. The sleeve 83 carries a two armed dog 100 and a plate spring 101 one end of which bears on one end of one of the dog arms. The other pendant arm of the dog is in line with a stop 102 which is adjustably secured to the bracket 50. The bracket 49 carries a stop 103 which extends in the opposite direction. 95 As the sleeve 83 is moved away from the cage, carrying with it the gripper and attached patch, the patch passes through the guide plates 104, which guide plates are secured to the arms 58 of the cage and extend 100 toward the plunger underneath the suction plate or recessed portion 44, of the plunger, as before described, and when the patch reaches its proper position in the recess in the suction plate and is held securely thereon, then the roller 98 on the tripper arm 97 strikes the curved projection 103 and rotates it downwardly, as in Fig. 4, which opens the arm 91 of the gripper and frees the gripping device from the patch. The plunger 110 then descends. At the commencement of the downward movement of the plunger, the sleeve 83 begins its movement in the reverse direction, that is, toward the cage, carrying with it the open jaw of the gripper. The 115 movements of the plunger and gripper carrying mechanism are so arranged that the plunger on its downward movement descends a sufficient distance before the gripper carrying mechanism on its movement toward the cage reaches the plunger and as the head of the plunger has descended below the gripper mechanism, this gripper mechanism passes over the plunger head. At the time of its arrival to its position in close proximity to the cage, the lower arm of the dog strikes the stop 102. Just previous to this, the rod 73 has been lowered, leaving a patch in the manner previously described and alined it with the grooves in the guideways 104. The 120

contact of the pendant arm of the dog with the stop 102, has freed the other arm from contact with the arm 97, tripped it, and allowed the spring 90 on shaft 89 to operate to 5 rotate that shaft so as to move the arm 91 of the gripper downwardly again to grip the end of a patch in the manner previously described. The stop 102 is made adjustable for the purpose of enabling the machine to be 10 readily put together and adjusted to compensate for wear.

In the operation of the machine, as before described, the patch is not positively guided; except when it is moving through the guide 15 plates 104. These guide plates serve to straighten out and align the patch so that its sides will be as near parallel to the sides of the opening in the envelop blank as may be. At two other points in its movement, to wit, 20 lifting it from the pile of patches and presenting it to the guideways in the guide plates 104, and after it leaves the guide plates, and is drawn along the face of the plunger of the folding mechanism, the patch has a tendency to become laterally disaligned; 25 in other words, there is a tendency for the longitudinal axis of the patch to get out of alignment or parallelism with the longitudinal axis of its movement, which would result in the patch being misplaced, with relation 30 to the opening in the envelop blank. In order to preserve the proper alignment in the application of the patch to the envelop blank, so that the edges of the patch will be in substantial parallelism with the edges of the 35 opening in the blank, and additionally in order to insure against the patch getting askew while being drawn through the guide plates, I employ the mechanism shown in 40 detail in Fig. 3 previously described.

The drawing indicates two points of contact of the frame with the patch, one at the point where the lever engages a patch substantially along the longitudinal center thereof, and the other at or adjacent the inner edge of the patch. This two-point contact will prevent the patch from becoming skewed. The inner contact is a resilient one, so that the forceful pressure of the finger 91 45 of the gripper against the patch will be relieved, thereby avoiding injury to the patch, at the same time preventing the patch from slipping.

Also, in the operation of the machine, if 50 the bearings of the parts immediately connected with the gripping device, especially over the shaft 89, become worn, which has a tendency to disalign the gripping surfaces of the gripper in two or more directions, the 55 resiliently controlled gripper compensates for this wear and maintains a uniform area of gripping surfaces for the patch, regardless of the amount or direction of the normal wear of the parts.

60 Figs. 12, 13, 14 and 15 show the operation

of the plunger after it has received the patch. In Fig. 12 it is holding the same in the recess 44 by the suction of the pump A shown in Fig. 11. The envelop blank has been drawn by the arms 26 from under the gumming dies 11, 12 and 13 and rests upon the creasing plate 30 (Fig. 12). In Fig. 13 the plunger strikes the envelop blank and forces the same through the opening 34 therein, so that the flaps are folded upward. The suction from the pump still holds the patch in contact with the suction plate of the plunger and in Fig. 14 the blank is shown forced through the creasing plate 30 so that the flaps on the envelop blank have been folded 70 upwardly and then the pump reverses operations and blows out air which begins to force the patch against the surface of the blank and over the opening therein. In Fig. 15 the plunger has reached the bottom of its movement and forced the blank against a folding bed 105, suitably situated below the creasing plate 30 where the sealing of the flaps takes place, which operation is performed by any well known or desired means. 75

Having described my invention, it is obvious that the same is not restricted to the precise embodiment herein shown but is broad enough to cover all structures coming 80 within the scope of the annexed claims. 95

What I claim is:

1. In an envelop machine, the combination with mechanism for gumming an envelop blank, of flap creasing mechanism, of mechanism for withdrawing said gummed blank from the gumming mechanism and removing the same to the flap creasing mechanism, a folding bed, a plunger adapted to co-operate with the creasing mechanism, pneumatic mechanism for retaining a patch on 100 said plunger while the blank is being creased and for ejecting the patch from said plunger onto the blank when said blank reaches the folding bed. 105

2. In an envelop machine, the combination with mechanism for gumming an envelop blank, of a creasing plate, of mechanism for withdrawing said blank from the gumming mechanism and removing the same to the creasing plate, a plunger for co-operating with the creasing plate in creasing the blank, pneumatic means for holding a patch on the plunger and out of contact with the blank while the creasing operation is performed, said pneumatic means adapted to eject the patch from said plunger onto the blank after the creasing operation has been completed. 110

3. In an envelop machine, the combination with mechanism for gumming an envelop blank, a creasing plate, of mechanism for withdrawing said blank from the gumming mechanism after the gum has been applied and carrying the same to the creasing plate, a patch table, a recessed plunger, mechanism for moving a patch from said 125 130

table to the recess in the plunger, pneumatic means for retaining the patch on said plunger within the recess formed therein while the plunger, in coöperation with the creasing plate, creases the blank, said pneumatic means ejecting the patch from the plunger onto the blank after the creasing operation has been performed.

4. In an envelop machine, the combination 10 with mechanism for gumming an envelop blank, creasing mechanism, of mechanism for withdrawing said blank from the gumming mechanism after the application of the gum to the envelop blank and transferring said blank to the creasing mechanism, a plunger adapted to coöperate with said creasing mechanism, mechanism for carrying a patch to said plunger, means for holding a patch on said plunger and away 20 from the surface of the envelop blank while the same is being creased and means for applying said patch over the opening in the envelop blank after the creasing operation is completed.

25 5. In an envelop machine, the combination of mechanism for gumming an envelop blank, a creasing plate, means for transferring said envelop blank to the creasing plate, a plunger adapted to coöperate with said creasing plate, a patch table, means for transferring a patch from said patch table to the plunger, means connected to the plunger for retaining the patch on the plunger and preventing same from contacting 35 with the surface of the envelop blank while the creasing operation is in progress, and applying said patch to the opening in the envelop blank after the creasing operation is completed.

40 6. In an envelop machine, the combination of mechanism for gumming and lifting an envelop blank, a creasing plate, means for separating said blank from the gumming mechanism, grippers for transferring said envelop blank to the creasing plate, a patch table, a plunger adapted to coöperate with said creasing plate, means for lifting a patch from said table, mechanism for transferring the lifted patch to the plunger, said plunger 45 creasing the envelop blank on the creasing plate and then applying said patch to the opening in said blank when said creasing operation is completed.

7. In an envelop machine, the combination 50 of mechanism for gumming and lifting an envelop blank, means for separating said blank from the gumming mechanism after the gumming operation is completed, folding mechanism, means for transferring the envelop blank to said folding mechanism, a patch table, mechanism for lifting a patch from said table, a plunger, means for withdrawing said lifted patch and transferring same to the under surface of said plunger, 55 said plunger creasing the envelop blank and

applying the patch over the opening in said blank when the creasing operation is completed.

8. In an envelop machine, the combination of means for gumming and lifting an envelop blank, means for removing said blank from the gumming mechanism, a creasing plate, means for transferring said blank to the creasing plate, a plunger having a recess and adapted to coöperate with said creasing plate, a patch table, means for lifting a patch from said table, means for transferring said patch to the plunger, means for holding said patch in the recess in the plunger so that the creasing operation of the envelop blank may be performed before the patch is applied by said plunger.

9. In an envelop machine, the combination with means for gumming and lifting an envelop blank, means for detaching said envelop blank from the gumming mechanism, creasing mechanism, means for transferring said envelop blank to the creasing mechanism, a plunger adapted to coöperate with said creasing mechanism, a patch table, mechanism for engaging the end of said lifted patch and carrying said patch beneath the plunger, means connected to said plunger whereby said patch will be received by said plunger as the patch passes beneath the same, said means being adapted to hold said patch on the under side of the plunger without the patch contacting with the blank.

10. In an envelop machine, the combination with means for gumming an envelop blank, creasing mechanism, means for transferring the gummed envelop blank to said creasing mechanism, a plunger adapted to coöperate with said creasing mechanism, a patch table, means for transferring a patch from said table to the under surface of said plunger, said plunger having a recess to receive the patch, pneumatic means for retaining said patch on the surface of the plunger within the recess formed therein and away from the surface of the envelop blank while the plunger performs the creasing of the flaps of the envelop blank said pneumatic means also adapted to force the patch against the surface of the envelop blank after the creasing operation is completed.

11. In an envelop machine, the combination with gumming mechanism for an envelop blank, creasing mechanism, mechanism for transferring the gummed blank to the creasing mechanism, a plunger adapted to coöperate with the creasing mechanism having a recess and perforations leading to said recess, means for causing air suction to pass through said perforations to support a patch against the top of said recess while the plunger creases the flaps of the envelop blank.

12. In a machine of the class described, a patch table, a creasing plate and a recessed

plunger, means for removing a patch from said table to the plunger, pneumatic means for holding said patch in the recess in said plunger out of contact with an envelop blank forced through the creasing plate by said plunger.

13. In a machine of the class described, a plunger having a recess, said recess being of a size to hold a patch, said plunger also having openings extending through it to the recess and means for producing air suction through said openings to cause a patch to be held on the plunger in the recess therein.

14. In an envelop machine, the combination with means for gumming an envelop blank, mechanism for transferring the gummed envelop blank to creasing mechanism, a patch table, means for lifting a patch from said table, a recessed plunger, a carriage movable toward the patch table, grippers on said carriage for engaging the lifted patch and transferring same to the recess in the plunger and means on the carriage for releasing the hold of the grippers on the patch when said patch is beneath the plunger whereby said patch may be received in said recess.

15. In an envelop machine, the combination with means for gumming an envelop blank, means for transferring said blank to creasing mechanism after the same has been gummed, a patch table, a recessed plunger, an air tube for lifting the uppermost of said patches from said patch table, a movable carriage, means on said carriage for engaging the lifted patch and transferring the same to the plunger where said patch is received from the patch carrying means into the recess in the plunger, and means on said carriage for causing the patch, engaging means to disengage the patch when the carriage reaches the plunger.

16. In an envelop machine, the combination with means for gumming an envelop, a patch table, a plunger having a patch holding recess, a pivoted air tube for lifting a patch from said table, guides for said lifted patch, grippers engaging said lifted patch and transferring the same to the recess in the plunger and mechanism connected to said grippers for causing the same to separate when a position beneath the plunger has been reached.

17. In an envelop machine, gumming means for an envelop blank, a patch table, a plunger having a patch holding recess, a pivoted air tube for lifting a patch from said table, guides for said lifted patch, grippers passing between the guides for engaging said patch and transferring the same to the recess in the plunger, and mechanism for causing the grippers to disengage the patch when said patch has reached a position beneath the recess in the plunger.

18. In an envelop machine, the combina-

tion with a plunger having a patch holding recess, a patch table, means for lifting the end of the uppermost patch from said table; guides for the edges of said patch, a movable carriage, grippers on said carriage for engaging the lifted end of the patch and transferring said patch to a point beneath the recess in the plunger, suction means in said plunger for causing the patch to adhere to its under surface in the recess therein and means connected to the grippers for causing the same to release the patch when engaged by the plunger.

19. In an envelop machine, the combination with a plunger having a patch holding recess, a patch table, a pivoted air tube for lifting the uppermost patch from said table, a carriage movable under said plunger and having a pair of grippers for engaging the lifted patch, means for causing the grippers to engage said patch when the carriage has reached a point adjacent the patch table, means for causing the grippers to release said patch when the patch has reached a point below the recess in the plunger and means for causing air suction to pass through the plunger for causing the patch to adhere to its under surface within the recess when released by the grippers.

20. In an envelop machine, the combination with a patch table, means for lifting a patch from said table, a frame, a carriage movable on said frame, grippers on said carriage for engaging the lifted patch, a stop adjacent one end of the frame, mechanism on the carriage for engagement by the stop to cause said grippers to engage the patch, a stop adjacent the other end of the frame for engaging the mechanism on said carriage and causing the grippers to disengage the patch and a plunger and means connected to said plunger for causing the patch to adhere to the under surface of said plunger when said patch is released by the grippers.

21. In an envelop machine, the combination with a patch table, means for lifting a patch from said table, a frame, a carriage movable on said frame, a pair of grippers on said carriage for engaging the lifted patch, a rod pivotally mounted in the carriage, one of said grippers being mounted upon said rod, a stop adjacent one end of the frame, mechanism connected to said pivotal rod for engagement by said stop whereby the grippers are caused to engage the lifted patch, a stop adjacent the other end of the frame for causing the pivotal rod to pivot and separate the grippers whereby the patch carried by said grippers is released.

22. In an envelop machine, the combination with a patch table, mechanism for lifting a patch therefrom, grippers for transferring said patch, one of said grippers having an opening therein, a spring secured to

said gripper with a section of yielding material secured to said gripper and extending through said opening whereby a yielding or resilient contact between the grippers is secured.

23. In an envelop machine, the combination of means for gumming an envelop blank, creasing mechanism, means for transferring said envelop blank from the gumming means to said creasing mechanism, a plunger for creasing said envelop blank and applying a patch thereto, a patch table, means for transferring a patch from said table to the plunger, a recess in said 15 plunger for receiving the patch, said plunger having openings extending from said recess through a tube secured to the plunger, whereby suction passing through said plunger causes the patch to adhere to the 20 upper surface of the recess while the plunger is performing the folding operation and air pressure forced through said plunger after the folding operation is completed causes the patch to adhere to the envelop blank.
24. In an envelop machine, the combination with mechanism for gumming an envelop blank, a creasing plate, of mechanism for carrying the gummed blank to said creasing plate, a support beneath said creas-

ing plate, a plunger adapted to cooperate with the creasing plate, said plunger having a patch holding recess, means for transferring a patch to the plunger, and pneumatic means for holding said patch on the plunger within the recess formed therein, 35 said pneumatic means adapted to hold the patch into the recess and out of contact with the blank while the creasing operation is being performed, and adapted to force said patch on to the surface of the envelop blank 40 when said blank reaches the support beneath the creasing plate.

25. In an envelop machine, a creasing plate and a plunger adapted to coöperate with the same to crease an envelop blank, a 45 folding bed to which the blank is transferred by the plunger, the plunger having a recess for holding a patch, and means for causing air suction through said plunger to hold the patch in the recess while the blank is being 50 transferred to the folding bed by the plunger, said means acting to cause the patch to be applied to the blank when said blank reaches the folding bed.

Signed at the city of New York, county 55 of New York, and State of New York, this 29th day of November, 1915.

CARL O. EKVALL.
